UNITED STATES PATENT OFFICE.

ARCHIBALD BANNATYNE, OF WATERBURY, CONNECTICUT, ASSIGNOR TO
THE WATERBURY CLOCK COMPANY, OF SAME PLACE.

CLOCK-WINDING MECHANISM.

SPECIFICATION forming part of Letters Patent No. 427,292, dated May 6, 1890.

Application filed February 7, 1890. Serial No. 339,555. (No model.)

To all whom it may concern:

Be it known that I, ARCHIBALD BANNATYNE, of Waterbury, in the county of New Haven and State of Connecticut, have invented new 5 Improvements in Clocks; and I do hereby declare the following, when taken in connection with accompanying drawings and the letters of reference marked thereon, to be a full, clear, and exact description of the same, and 10 which said drawings constitute part of this specification, and represent, in—

Figure 1, a broken sectional view showing the front and back plates of a clock-movement, the mainspring thereof, the barrel 15 which incloses the said spring, the mainspring-arbor, the ratchet, and the winding-key; Fig. 2, a detached view in elevation, showing the ratchet in which my invention chiefly resides.

My invention relates to an improvement in 20 clocks, the object being to provide simple, cheap, and reliable means for securing a maintaining power on the train when the clock is being wound.

With these ends in view my invention consists in certain details of construction and 25 combination of parts, as will be hereinafter described, and pointed out in the claims.

In my improved construction I employ a ratchet A, having two hubs B and C made 30 integral with it and extending from its opposite faces. The inner hub B is reduced to form a shoulder D corresponding in depth to the thickness of the back movement-plate E, which is provided with an opening F, corresponding in size to the diameter of the said 35 hub, the extreme inner end of which receives the spring-barrel G, which is secured to the hub by the swaging down of the end thereof upon the inner face of the barrel. Under 40 this construction the ratchet-wheel bears directly against and is supported by the rear face of the movement-plate E, while the spring-barrel bears directly against and is supported by the outer face of the said movement-plate, whereby both the ratchet and 45 barrel are relieved from much strain and steadied. The said hub B is provided with a central opening H, receiving the inner end of the mainspring-arbor I, while the hub C is 50 provided with a larger threaded opening J,

adapted to receive the threaded nipple K of the winding-stem L. The threaded opening J leads into the opening H, so that the inner end of the winding-arbor may be oiled from the outer end of the hub C. A shoulder M, 55 formed in the hub where the two openings H and J merge into each other, prevents the threaded nipple K of the winding-stem from entering the hub too far. The outer end of the mainspring N is attached to the barrel 60 mainspring-hook O, while the inner end of the said spring is attached to the arbor mainspring-hook S in the usual manner. Now, when the clock is wound by the winding-key the barrel and ratchet will revolve together, 65 and thereby wind the mainspring, the power of which, however, will not be removed from the train during the operation of winding it, inasmuch as the barrel and ratchet rotate entirely independently of the arbor to which 70 one end of the mainspring is attached.

By making the ratchet and the two hubs in one piece and shouldering the inner hub to conform to the thickness of the back movement-plate, so that both the ratchet and barrel will bear against the said plate and be supported thereby, I secure a very simple and strong construction, which is cheap to produce and assemble, and durable in use. 75

I am aware that it is not broadly new to 80 secure the ratchet and mainspring-barrel together and rotate them independently of the mainspring - arbor, and do not therefore broadly claim that construction, but only my peculiar form and arrangement of parts. 85

Having fully described my invention, what I claim as new, and desire to secure by Letters Patent, is—

1. In the winding mechanism of a clock, a ratchet having two hubs made integral with it and projecting from its opposite faces, one of the said hubs being shouldered to correspond to the thickness of the movement-plate through which it passes and in which it rotates, so that the ratchet and the mainspring-barrel, which is secured to the shouldered end of the hub on the opposite side of the plate, will bear directly against and be supported by the opposite faces of the same, substantially as described. 95

2. In the winding mechanism of a clock, the combination, with the mainspring-barrel, mainspring-arbor, and the winding-key of the clock, of a ratchet having two hubs made 5 integral with it, and respectively projecting from its opposite faces, one hub having an opening to receive the winding-key and the other hub being shouldered to conform to the thickness of the movement-plate through 10 which it passes, and having the mainspring-barrel secured to it on the opposite side of the plate from the ratchet, so that the ratchet

and the barrel will bear directly against and are supported by the opposite faces of the said plate, and having an opening formed in 15 it to receive one end of the mainspring-arbor, the said openings formed in the hubs communicating with each other, substantially as described.

ARCHIBALD BANNATYNE.
